UNITED STATES PATENT OFFICE.

HUGO J. BLOOM, OF MOLINE, ILLINOIS.

SIFTER.

Application filed July 2, 1928. Serial No. 290,016.

The present invention pertains to a sifter, more especially one designed for the sifting of flour for cakes and the like, though it will be understood that the same is useful for other purposes as well.

Among the objects of this invention are to produce a novel sifter having an improved action comparable to the old fashioned hand-sifter but much improved thereover; to provide a simple mechanism of the character stated; to provide an apparatus of the character indicated which is easy to manufacture and of inexpensive construction; to provide an apparatus of the character indicated which will not readily get out of repair; and such further objects, advantages, and capabilities as will hereafter appear and as are inherent in the construction disclosed herein. My invention further resides in the combination, construction and arrangement of parts illustrated in the accompanying drawing and, while I have shown therein what is now considered the preferred embodiment of my invention, I desire the same to be understood as illustrative only and not as limiting said invention.

In the drawing annexed hereto and forming a part hereof, Fig. 1 is an elevation showing a sifter in accordance with my invention; Fig. 2 is a plan view of the construction shown in Fig. 1.

Referring more in detail to the annexed drawing, numeral 1 denotes the handle which is provided with a forked head 2, the arms 35 of which are turned up as indicated at 3 to furnish pivotal supporting means for the container 5. Trunnions 4 are located upon the external surface of the container 5, near the upper end thereof and support the container, pivotally, between the upper ends of the arms 3. It will be seen from this that the container is capable of swinging back and forth upon these pivots and is in a condition of stable equilibrium with respect thereto.

On its lower end, the container has a flange 6 turned in to support a plurality of screens 7, any desired number of which may be placed in the container. For example, if it is desired to have the flour sifted four times, then four 45 screens would be placed in the container. If it is desired to sift the flour a larger or smaller number of times, then a larger or smaller number of sifting elements will be placed therein.

In order to pivotally mount actuating means upon the head of the handle 1, a boss

is formed upon one of the arms thereof and this is perforated for the reception of the bolt 8. This bolt passes through the arm, the boss, and the center of the plate 9. This plate 60 has a flange 10 around the outer edge thereof for engagement with a pair of lugs or pins 11 projecting from the side of the container 5. The flange is located between these projections so that as the plate 9 is rotated about 65 its pivot 8 the container will be caused to swing forwardly and backwardly upon its pivot 4. Means 12, in the form of a handle secured to the plate 9 serves as means whereby the plate can be turned upon its pivot. It 70 will be seen from this disclosure that when the plate is turned through a complete circle the container will be caused to move backwardly and forwardly four times, thus causing a quick reversal of direction. This will 75 cause the flour to be shaken through the screens 7 as will be readily understood. It is believed that the construction and operation of this device will be fully understood from the foregoing description taken in connection with the annexed drawing and that further description will therefore be unnecessary.

Having now described my invention, I claim:

1. A sifter comprising a container for powdered or granular material, a handle pivoted thereto so that the container may be caused to swing with relation to the handle, and cooperating means connecting the handle and 90 container whereby the latter may be actuated to swing with relation to the former.

2. In a sifter, a handle having a forked head provided with angular extensions, a container pivoted to the extensions, spaced 95 projections on the container at a distance from the pivot, pivoted means on said head adapted to cooperate with the projections to cause the container to swing rapidly on its pivots.

3. In a sifter, a handle having a forked head provided with angular extensions, a container pivoted to the extensions, spaced projections on the container at a distance from the pivot, a plate pivoted on the head 105 adjacent the projections, said plate having an angular flange extending toward the container and between the projections, and means for rotating the plate on its pivot.

4. In a sifter, a handle having a pair of 110 arms extending laterally and upwardly, a container having sifting screens therein piv-

oted adjacent the upper ends of the arms, a plate pivoted adjacent the lower end of one of the arms, said plate having a flange around its periphery extending inwardly toward the container, and a pair of spaced lugs on the container adjacent an edge of the plate, the flange on the plate extending between the

lugs and serving, as the plate is rotated, to turn the container rapidly back and forth upon its pivots.

In witness whereof, I hereunto subscribe my name to this specification.

HUGO J. BLOOM.
